US0D1008586S

(12) **United States Design Patent** (10) Patent No.: **US D1,008,586 S**
(45) Date of Patent: ** Dec. 19, 2023

(54) **ROBOTIC POOL CLEANER**

(71) Applicant: **Beijing Smorobot Technology Co., Ltd**, Beijing (CN)

(72) Inventor: **Jie Tang**, Beijing (CN)

(**) Term: **15 Years**

(21) Appl. No.: **35/515,492**

(22) Filed: **Aug. 26, 2022**

(80) **Hague Agreement Data**

Int. Filing Date: **Aug. 26, 2022**

Int. Reg. No.: **DM/224195**

Int. Reg. Date: **Aug. 26, 2022**

Int. Reg. Pub. Date: **Oct. 28, 2022**

(30) **Foreign Application Priority Data**

Aug. 1, 2022 (CN) 202230496963.0

(51) **LOC (14) Cl.** **15-05**

(52) **U.S. Cl.**
USPC **D32/21**

(58) **Field of Classification Search**

USPC D32/15-25, 31-34
CPC A47L 5/24; A47L 5/367; A47L 7/0076;
A47L 7/008; E04H 4/1654; E04H 4/1663;
E04H 4/1672

Primary Examiner — Kimberly Barnes

(57) **CLAIM**

The ornamental design for robotic pool cleaner, as shown and described.

DESCRIPTION

1. Robotic pool cleaner

1.1 : Perspective

1.2 : Perspective

1.3 : Front

1.4 : Back

1.5 : Left

1.6 : Right

1.7 : Top

1.8 : Bottom

1 Claim, 8 Drawing Sheets
